Primary Examiner — Susan Bennett Hattan*Assistant Examiner* — Elizabeth S Ko(74) *Attorney, Agent, or Firm* — Guice Patents PLLC(57) **CLAIM**

The ornamental design for a curtain lower weight, as shown and described.

DESCRIPTION

FIG. 1 is a perspective view of a curtain lower weight;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The drawings contain a symbolic break symbol. The claim terminates at the line that includes the break symbol.

1 Claim, 4 Drawing Sheets
